Specification for Design.

Patented June 27, 1922.

Application filed March 24, 1921. Serial No. 455,165. Term of patent 14 years.

To all whom it may concern:

Be it known that I, MORRIS GOLOMB, a citizen of the United States, and a resident of New York, in the county of New York and State of New York, have invented a new, original, and ornamental Design for an Abdominal Protector for Boxers, of which the following is a specification, reference being had to the accompanying drawing forming part thereof.

The figure is a perspective view of an abdominal protector for boxers, showing my new design.

I claim—

The ornamental design for an abdominal protector for boxers as shown.

MORRIS GOLOMB.
